AUTOMATIC DEVICE FOR CONTROLLING
CIRCUITS FOR INTERNAL-COMBUSTION
ENGINES

Walter L. Wright, Flushing, N. Y.

Application April 16, 1947, Serial No. 741,900

4 Claims. (CL 290—37)

1

This invention relates to a device for controlling the operation of a starter for internal combustion engines, and more particularly to a device wherein the manual closing of the ignition switch will cause an electric current to flow to, and actuate the starting motor and start the engine, which, when started, will automatically break the circuit supplying E. M. F. to the starter and stop same, and, further, when the engine stalls or stops from any cause, the electric circuit will automatically close to again actuate the starter and restart the engine.

Numerous appliances of this character have been devised but they have been only partially efficient, due mainly to the failure of various controlling elements in the device to respond to the varying conditions under which the device must operate during the starting period of the engine and, at times, while the engine is running under its own power.

Various elements involved in the starter controlling unit are electrically connected and operated, and must operate in quick succession, the time period of each stage of the operation being measured in split seconds. Any lag in the operation of any part will cause the apparatus to fail.

The successful operation of devices of this character depends, in great part, upon the suctional draw or vacuum from the intake manifold of the engine to which the device is connected and, as this vacuum varies in intensity during the starting interval and at times during the running of the engine, provision must be made in the device to compensate for this fluctuation so that the elements comprising same will be fully responsive at all times during the vacuum period, which may vary from a 22 inch reading upon a vacuum gauge down to zero.

Another factor which will cause failure in operation is the lack of sufficient E. M. F. through the device due to failure of the generator for any reason.

None of the devices at present known has overcome these factors, which contribute to failure of such a device.

It is an object of this invention to provide a device of the character described which will include means to overcome all of the above mentioned defects, and will successfully function at all times and under all normal and abnormal conditions.

Another object of this invention is the provision therein of positive means to automatically cut out the E. M. F. to the starting motor as soon as the engine is running on its own power and which will automatically reestablish the E. M. F.

to the starting motor and restart the engine should it stall for any reason.

A still further object of this invention is the provision of an organization in which the constituent elements are so arranged structurally and functionally as to assure improved results with materials and members which may be manufactured at reasonable cost, may be easily assembled and which will be efficient in operation with minimum wear to the parts.

This invention possesses other objects and features of advantage some of which, with the foregoing, will be set forth in the following description and in the claims wherein parts will be identified by specific names for convenience, but they are intended to be as generic in their application to similar parts as the art will permit. In the accompanying drawings there has been illustrated the best embodiment of the invention known to me, but such embodiment is to be regarded as typical only of many possible embodiments, and the invention is not to be limited thereto.

The novel features considered characteristic of my invention are set forth with particularity in the appended claims. The invention itself, however, both as to its organization and its method of operation, together with additional objects and advantages thereof, will best be understood from the following description of a specific embodiment when read in connection with the accompanying drawings, in which:

Figure 1 is a diagrammatical view of the electrical circuit and connected control elements in the device.

Figure 2 is a view of the device looking toward the bottom of the housing with part of the housing broken away.

Figure 3 is a side view of same with most of the side wall of the housing broken away, and shows the device standing on end.

Figure 4 is a front elevational view with most of the front wall of the housing broken away, showing the cover in the lower portion of the view.

Figure 5 is a detail of one of the control switches in the device.

Figure 6 is a similar detail but shows a different position of the parts of same.

Referring in detail to the parts, 11 designates the bottom of a cabinet or housing, 12 and 13 the front and rear walls thereof respectively, 14 and 15 the side walls, and 16 the removable cover which is attached to the cabinet by means of screws 17. A toggle switch 18, may be attached

to the cabinet in any convenient location and terminals, or binding posts 19, 20 and 21 are suitably attached to the cover 16, and properly insulated therefrom.

A relay, or magnetic switch 22, is secured to the cover and insulated therefrom. The said relay switch is mounted upon a U-shaped member 23 (Figure 4), having upwardly extending arms 24 and 25. The arm 24, extends upwardly to a point slightly above a magnet spool 26, carrying, pivotally attached to it, an armature 27, the contact end 28, of which is held in its uppermost position by means of a spring 29. In its uppermost position the said end 28, of the armature 27, contacts a point 30, upon the upper turned-over end of a bracket arm 31, which is secured to the upright arm 25, but insulated therefrom. This armature will break the contact at 30, when the core 32, of the magnetic spool 26, is electrically energized as hereinafter described.

A micro-switch, having a body portion 33, of insulating material, is attached to the said cover 16. This micro-switch is of the usual construction and is adapted to make or break either one of two circuits, and when set in position in the cabinet a plunger 34, extending from a piston 35, within a cylinder 36, engages a pin 37, having a cap or button 38, of insulating material. The said cap 38, in turn, engages a spring arm 39, to operate a second spring arm 40, through the use of the arcuate spring 44, when the said plunger 34, moves against or away from the said pin 37. A tube 41 connects a compartment 42, with the intake manifold 43 (Figures 1 and 5), of the engine. With the engine running, the suction through the tube 41, draws the piston 35, down against the force of a spring 44, when the micro-switch will assume the position shown in Figure 5. When, however, the engine is idle or inoperative no vacuum is created, and the pull on the piston 35, ceases, allowing the spring 44, to function and force the plunger 34, against the pin 37, and set the micro-switch in the position shown in Figure 6.

The normal, or inactive position of the micro-switch when free, or unattached and not acting in coordination with other parts is as shown in Figure 5. The normal position of the same, however, when connected in the device herein described is as shown in Figure 6.

Carried upon, and arranged in any suitable manner upon the cover 16, is a capacitor unit 45, which is adapted to supply electrical energy to the relay 22, when the E. M. F. from the battery, or generator is too low to energize same. Resistor units 46 and 47, are disposed in the circuits as shown, and their function will be hereinafter described in connection with the description of the diagram shown in Figure 1.

As shown in Figure 5, a contact point 48, upon one side of the free end of the spring arm 40, engages a point 49, upon the bracket 50, and is connected in an electric circuit by the conductor 51, which is attached to the lug 52, formed upon said bracket 50. In Figure 6, a second contact point 53, upon the opposite side of the said free end of the spring arm 40, engages a point 54, upon a U-shaped plate 55, attached to the micro-switch body 33, and is connected in an electrical circuit by means of a conductor 56, which is, in turn, attached to a lug 57, formed upon the said U-shaped plate 55. A conductor 58, is attached to a lug 59, formed upon an

angular plate 60, which, in turn, carries the said spring arm 40, and provides a means for connecting said arm within an electrical circuit, as will be hereinafter more fully explained.

5 The description of the electrical hookup will best be understood when read in connection with the diagram of Figure 1, to which reference is now made.

To start the engine to which this device is attached, the ignition switch 61, is closed by means of a key 62, whereupon an electric circuit flow is established, which starts at the battery B, and runs through lines 63 and 64, to ammeter 65, passes along line 66, to ignition switch 61, thence through line 67, to the primary coil of an induction coil 68, which is grounded at the distributor 71. From the secondary coil of the induction coil 68, a line 70, leads a high tension current to the distributor unit 71, from whence the current is distributed to various spark plugs on the engine. The secondary coil of the induction coil 68, is grounded at 72.

An electrical current also flows from the switch 61, through the line 73, to the binding post 20, 25 through the line 74, to a toggle switch 75, and from the toggle switch through the line 58, to the spring arm 40, of the aforementioned micro-switch 33. From the spring arm 40, the electrical 30 flow is across the contact points 53 and 54, through the U-shaped plate 55, and lug 57, to the conductor 56, which carries the current to the contact point 30, into the armature 27, of the relay 22. From this armature the current 35 flow is through the conductor 76, to the binding post 19, and thence through the line 77, to a solenoid 78, and to the ground 79.

A completed circuit has now been established

and energizes the coil of the solenoid 78, to close the battery circuit at the point 80 and 81, there-

40 by allowing an electric flow from the battery B, which is grounded at 91, through the line 63, the line 82, across closed points 80 and 81, through the line 83, to starter S, and there grounded at 84. The starter S, is now energized

45 and rotates to start the engine. As soon as the engine picks up speed, a vacuum is created in the intake manifold 43, which makes connection by means of the aforesaid tube 41, with the said cylinder compartment 42. This vacuum will

50 draw the said piston 35, down into the said cylinder compartment 42, as shown in Figure 5, to break the circuit at the points 53 and 54 breaking the said solenoid circuit, and establishing a

55 new contact through the contact points 48 and 49, to allow a current flow through the bracket member 50, lines 51 and 85, resistor 46, lines 86 and 87, and coil 26 of relay 22, and is grounded at 88, thereby energizing said coil to attract said

60 armature 27, and break the contact at 30, thus breaking the circuit to the solenoid 78 to break the starter circuit, at the points 80 and 81, and deenergizing and stopping the starter S.

With the engine running, the generator G, 65 grounded at 92, will come into action and generate E. M. F. which will flow from the generator along line or conductor 89, to the terminal or binding post 21, through line 90, resistor 47, and lines 86 and 87, to the coil 26, of the relay 22,

70 to ground 88, thus holding the armature 27, down to keep the starter circuit open at the point 30.

The continued normal running of the engine will establish a vacuum in the intake manifold 43, which is transmitted through the tube 41, to

75 the cylinder 42, to draw the piston 35, its con-

nected plunger 34, and insulator button 38, downwardly to release the spring arm 40, of the micro-switch 32, thereby bringing the points 48 and 49, into contact, as shown in Figure 5. This action closes the battery circuit at the points 48 and 49, and permits an electrical flow to the capacitor 45, to charge same. The said capacitor is grounded at 94, and may also be charged by the generator G, when the E. M. F. from the generator is also holding down the armature 27, of the relay 22, to keep the starter circuit open and the starter inoperative.

This description has so far not considered any of the retarding factors which might interfere with the efficient operation of the device. One of the principal retardative factors has to do with the varying vacuum created in the intake manifold and transmitted, by tubular connection, to a cylinder and piston which operate a micro-switch in the device, as has been hereinbefore briefly explained.

Considering, then, an engine having a multiplicity of cylinders and pistons, there will always be one cylinder and its piston operating on its intake stroke while the engine is running, and the successive operation of each cylinder will create a constant vacuum in the intake manifold. This vacuum increases or decreases according to the speed of the engine, in the following manner:

In starting an engine, the pistons, during their intake strokes will draw into the cylinder a charge of raw gas and create a vacuum in the intake manifold, which will register approximately ten (10) inches upon a vacuum gauge reading. After the engine has started and continues running, the vacuum will register about twenty-two (22) inches on the vacuum gauge. When the engine is running at idling speed, the vacuum will register about fifteen (15) inches, and when the throttle in the carburetor is suddenly opened wide to speed up the engine, the vacuum drops to approximately one (1) inch. The vacuum will also register approximately one (1) inch when the engine in an automobile is forced into a hard pull as when climbing a steep grade in high gear with the throttle wide open. Spring 96 gives the spring arm 40 its tripping action and makes possible the holding open of the circuit to the solenoid 78 even if the vacuum drops to as low as one-half inch. Semicircular shaped spring 96 requires a harder push up on pin 37 to close the circuit to the solenoid as shown in Fig. 6 than is necessary to permit it to trip to the position shown in Fig. 5. Spring 44 must exert a greater pressure to trip micro-switch 33 from the position shown in Fig. 5 to the position shown in Fig. 6 than is necessary to withstand the initial vacuum pull of 10 inches. Once the switch 33 has been permitted to trip to the position shown in Fig. 5 it will stay in that position holding the solenoid circuit open to almost zero of vacuum.

An added pressure is exerted by the arcuate member 96, of the said two way switch 33 (Fig. 6), which will be sufficient to overcome the opposed pressure of the spring 44 when the vacuum in the cylinder 36 drops to a point below 8''. The said added pressure will be sufficient to hold the said relay circuit closed at the contact points 53 and 54 when the said vacuum drops below 8''.

The vacuum created in the intake manifold 43, is adapted, through the connecting tube 41, to actuate the piston 35, in the cylinder 36, as has already been set forth. However, when starting an engine the pressure of the spring 44, must be

strong enough to withstand the vacuum pull of about ten inches against the piston 35, in order to keep the solenoid circuit closed at the points 53 and 54, in the micro-switch 33, thereby actuating the solenoid 78, and closing the battery switch at 80—81, to allow a current flow from the battery B, to the starter S, and hold the solenoid circuit closed until the engine gets under way and the vacuum increases sufficiently to overcome the force of the spring 44.

With the engine running, the vacuum increases to pull the piston 35, and its attached plunger 34, downwardly, releasing the micro-switch and changing the contact points from 53—54, to the points 48—49, thereby breaking the solenoid circuit and closing a circuit to the relay 22, and capacitor 45 and, in the meantime, keeping the solenoid circuit open to prevent a current flow to the starter.

It is essential that the solenoid circuit be kept open at all times while the engine is running, and when the vacuum pull is as low as one (1) inch and not sufficient to overcome the force of the spring 44, the added pressure of springs 39, 40 and 96, in the micro-switch 33, will overcome the lack of vacuum pull and force the plunger 34, downwardly to open the solenoid circuit at the micro-switch. There is sufficient pressure in the micro-springs 39, 40 and 96 to hold the plunger 34, against upward movement as long as the vacuum pull is above zero.

Should the vacuum drop to zero when opening the throttle wide while the engine is running, allowing the micro-switch 33 to close the circuit at 53—54, the capacitor 45, releases a stored-up charge of electrical current to the relay 22, keeping it energized to hold the solenoid circuit open at points 30 until sufficient vacuum is created to pull the plunger down and break the solenoid circuit at the micro-switch 33 at points 53—54.

In the particular arrangement and connections of the micro-switch and vacuum unit just described, the said springs 39 and 40 in the said micro-switch, coordinating with the vacuum in the chamber 42 are sufficient to offset the outward pressure of the plunger spring 44 and prevent the closing of said contact points 53 and 54 while the engine is running and the vacuum is below that required to open said contact points 53 and 54, thereby preventing the energization of the solenoid circuit.

A resistor 46, is disposed in the lines 85, 86 and 87, leading to the relay 22, to retard slightly and thus prolong the discharge flow from the capacitor into the relay coil 26, to keep the relay energized for a period of about three (3) seconds, or long enough to hold the relay active until the E. M. F. output from the generator G, has reached a point sufficiently high to energize the relay and/or hold the relay active until the vacuum is sufficient to break the circuit at the micro-switch 33.

A second resistor 47, is connected in the line 90, leading to the generator G, to force the electrical charge of the capacitor 45, into the relay 22, and prevent its discharge through the generator line 90, when the generator output is low.

Should the engine, for any reason, stall, the capacitor 45, will discharge a current through lines 93 and 85, resistor 46, and lines 86 and 87, to the relay and energize same, thereby holding the solenoid current open until after the engine has come to a stop. When the engine comes to a stop for a split second, the compression in a cylinder can cause the engine to turn slightly.

in a reverse direction, at which time the capacitor energizing the relay will keep the solenoid circuit open to prevent the operation of the starter, and allow the engine to come to an absolute stop before the starting motor goes into operation to start the engine. This function of the capacitor prevents the clashing of the gear on the starting motor and the gear on the flywheel.

Most engines, at the present time, are provided with a solenoid suitably located at the starter, and on such engines the device, including the parts within the box outlined by dot-dash line in Figure 1, may be suitably mounted on the engine and connections made to the parts shown outside the box.

On engines not having a solenoid, provision may be made to supply such a unit.

The device will function under all normal or abnormal conditions and speeds of the engine, even when the E. M. F. from the generator fails, due to a defective generator or the breaking of the driving belt of the generator or other cause.

Three methods are employed to break, and keep open the solenoid circuit to keep the starter inactive while the engine is running: (1) by the vacuum controlled micro-switch, (2) E. M. F. from the generator, and (3) by the battery current in conjunction with the capacitor; either one or all three will keep the circuit open.

The above description has set forth the use of the device in conjunction with an automobile engine but the device may also be employed in connection with any form of internal combustion engine. Attachment screws 85, may be provided to afford a means of securing the device to an internal combustion engine.

An important function of the capacitor 45 is to hold the said armature circuit open for a short period of time until the engine comes to an absolute stop before allowing the said solenoid circuit to close and thereby prematurely crank the engine. Another important function of the capacitor is to electrically energize the relay to keep the solenoid circuit open, preventing the starter from operating and allowing the engine to come to a stop before starting same and thus preventing the harmful clashing of gears.

The force of the arcuate spring 96 exerts an additional pressure to the spring arm 46 as it engages the piston rod 31 thereby holding the piston down against the pressure of spring 44 when the vacuum pull in the cylinder 36 drops.

During the cranking period the vacuum created is approximately 8". After the engine starts running under its own power the vacuum is increased above 8" but during a period of labor, such as going up hill, the vacuum drops below 8" for the duration of the laboring period.

When the engine is idling the vacuum will be approximately 18" but should the accelerator be suddenly opened, the vacuum will momentarily drop to 0".

I claim:

1. The combination with an internal combustion engine embodying an intake manifold, a generator driven by the engine, an electrically operated starting motor to crank the engine, a battery providing a current source, an electro-magnetic switch, a normally open circuit between the battery and starting motor, a closure member upon the electro-magnetic switch actuated by a coil of said electro-magnetic switch when energized, to close the said normally open circuit from the battery to the starting motor, and a manually operated ignition switch in the

battery circuit, of a circuit control device comprising a dual switch having a first and second terminal, a contact blade fixed at one end having electrical connection with the battery; dual contact points upon its free end engageable with the said first or second terminal upon the dual switch, an actuating blade connected to and coacting with the contact blade to urge the said contact points into or out of contact with either the first or second terminals upon the dual switch; an arcuate rolling spring pivotally connected between the said contact and actuating blades; an actuator pin upon said dual switch engageable with the actuating blade to actuate said contact blade, said contact blade being urged to close said battery to said electro-magnetic switch circuit at its first closed position when the engine is inactive and said ignition switch is closed, a relay having an armature switch arm pivotally mounted upon said relay and insulated therefrom, a contact element upon said armature switch arm engageable with a fixed contact element electrically connected to the first terminal upon said dual switch, said armature having electrical connections with the grounded coil of said electro-magnetic switch, a spring element between one end of said armature and the frame of said relay to urge said contact point upon said armature into contact with said fixed contact element, said armature being urged by said spring element to a normally closed position to close said electrical circuit from said battery to said grounded coil of said electro-magnetic switch, thereby energizing said coil to actuate said closure member to close said battery-starter motor circuit when said manually operated ignition switch is closed, a grounded coil on said relay having electrical connection to said second terminal upon said dual switch thence to said battery when said contact blade of said dual switch trips from its said first closed position to its said second closed position after the engine becomes active, thereby energizing said coil of said relay to attract said armature switch arm to open said battery to said electro-magnetic switch circuit, said electro-magnetic switch circuit having also been opened at said dual switch when said contact blade tripped from its said first closed position, the said relay coil having a second electrical connection with said generator, said generator adapted to energize said relay coil when said battery circuit to said coil is open, a capacitor grounded at one terminal and having electrical connection with said relay coil to maintain same in an energized state for a short period of time after the current supply from said battery and said generator ceases, said capacitor having electrical connections with said battery and said generator, said capacitor being energized by either said battery or said generator, a resistor electrically connected between said capacitor and said relay coil to retard the current flow from said capacitor, a second resistor in the circuit between said generator and said relay coil to urge the current flow from said capacitor into said relay coil, a vacuum element having a vacuum chamber tubularly connected to said intake manifold upon the engine, a movable wall in said vacuum chamber, said movable wall having a stem extending therefrom and making contact with said actuator pin upon said dual switch, a spring element upon said stem to urge said stem into contact with said actuator pin of said dual switch,

2. The combination with an internal combustion engine of a circuit control device as defined in claim 1, wherein a force established by a predetermined degree of vacuum in the vacuum chamber coacting with the spring pressure of said actuating blade of said dual switch overcomes the urge of said arcuate rolling spring of said dual switch and said spring element upon said stem of said movable wall in said vacuum chamber causing said spring elements to yield until the expansive action of said arcuate rolling spring passes its critical point between said actuating blade and said contact blade causing said contact blade to trip from its said first closed position to its said second closed position when the engine becomes active.

3. The combination with an internal combustion engine of a circuit control device as defined in claim 1, wherein a force established by a predetermined degree of vacuum in said vacuum chamber coacting with the spring pressure of said actuating blade and expansive action of the said arcuate rolling spring of said dual switch creates a differential in pressure on said spring element upon said stem of said movable wall, said differential in pressure adapted to maintain said contact blade of said dual switch in its said second

closed position when the vacuum falls to a low degree while the engine is operating.

4. The combination with an internal combustion engine of a circuit control device as defined in claim 1, wherein said spring element upon said stem of said movable wall overcomes the urge of said actuating spring blade and the expansive action of said arcuate rolling spring between said actuating and said contact blades of said dual switch causing said actuating spring blade and said arcuate rolling spring to yield until the expansive action of said arcuate rolling spring passes its critical point thereby causing said contact blade of said dual switch to trip from its said second closed position to its said first closed position when the engine becomes inactive and the vacuum ceases.
